Primary Examiner — Sheryl Lane*Assistant Examiner* — Calvin E Vansant(74) *Attorney, Agent, or Firm* — Tucker Ellis, LLP; Patrick Clunk; Carlos Garritano(57) **CLAIM**

The ornamental design for a coating material container, as shown and described.

DESCRIPTION

FIG. 1 is a perspective view of a coating material container showing our new design;

FIG. 2 is a front view thereof;

FIG. 3 is a rear view thereof;

FIG. 4 is a top view thereof

FIG. 5 is a bottom view thereof

FIG. 6 is a left side view thereof; and,

FIG. 7 is a right side view thereof.

The broken lines depict portions of the coating material container that form no part of the claimed design.

1 Claim, 7 Drawing Sheets(56)
